[45] Date of Patent: **Jul. 7, 1998

[54] COMBINED KEY RING AND VEHICLE
WHEEL ORNAMENT

D. 279,459 7/1985 On D3/210

[76] Inventor: **Samuel Wilkins**, 1154 Rayle Cir.,
Elberton, Ga. 30635

Primary Examiner—Ralf Seifert

[**] Term: 14 Years

[57] **CLAIM**

[21] Appl. No.: **64,201**

The ornamental design for a combined key ring and vehicle
wheel ornament, as shown and described.

[22] Filed: **Dec. 24, 1996**

DESCRIPTION

[51] LOC (6) Cl. **03-01**

FIG. 1 is a perspective view of a combined key ring and
vehicle wheel ornament showing my new design, it being
understood that the back, unseen portion of the wheel, is not
part of the claimed design.
